GEORGE ENNIS FERGUSON, OF SPRING VALLEY, NEW YORK, AND LEWIS GOVERNEUR MORRIS TIMPSON, OF PLAINFIELD, NEW JERSEY, ASSIGNORS TO PYRENE MANUFACTURING COMPANY, OF NEWARK, NEW JERSEY, A CORPORATION OF DELAWARE.

FIRE EXTINGUISHER.

Application filed September 1, 1925. Serial No. 53,828.

This invention relates to fire extinguishers and is herein described as applied to a well known foam type of bucket extinguisher. Extinguishers of that type usually consist 5 of a pail containing a suitable liquid such as an aqueous solution, which is adapted to be put into action by the breaking out of a fire owing to the fact that the fire melts a fusible link, with the result that a chemical reaction is started in the water. This 10 usually produces a froth which overflows and blankets the fire which melted the link.

Bucket extinguishers have proved extremely effective and are widely used, but 15 are open to a serious objection in that the contained water evaporates at such a rate that frequent inspection and renewal of the water is required. In the absence of such periodic replenishing the fire extinguisher 20 may fail to work properly when a fire breaks out owing to the depletion of the necessary water. According to the present invention the area of liquid from which evaporation takes place is so greatly reduced that evaporation 25 is minimized and the extinguisher retains substantially its full liquid contents over a very long period of time.

It has been found possible to attain this 30 minimizing of evaporation without in any way diminishing the efficiency of the extinguisher and in fact in such a way that its efficiency is to some extent increased. In the form of the invention herein described this end is accomplished by providing an internal 35 apron spaced a little distance from the inner wall of the bucket or pail and dipping below the surface of the contained liquid with the result that only a small part of the liquid surface is exposed to the air. It is found 40 that a properly spaced apron of this kind in no way diminishes the efficiency of the extinguisher where a froth-forming aqueous solution is used, and advantageously confines the froth more closely to the walls of the 45 pail where it is overflowing.

Other features and advantages will hereinafter appear.

In the accompanying drawing Figure 1 is a sectional side view of a bucket extinguisher of the type described, embodying 50 the present invention.

Figure 2 is a plan view of the same, and

Figure 3 is a side view of the extinguisher seen in section in Figure 1.

In the form of the invention shown in the 55 accompanying drawings a bucket or pail 1 is filled up to a predetermined point with an aqueous solution of bicarbonate of soda, which may also contain an excess of bicarbonate of soda as well as a froth producing 60 ingredient. The bucket or pail 1 is usually circular and has a bottom 2 which is recessed upwardly from the lower end 3 of the side wall 4, thus providing a space in which a fusible link 5 will be protected from accidental blows and yet will be open to be heated by flames beneath it when the bucket 65 is suspended by the usual bail 6. The bail usually turns on ears 8 which are held by rivets 9 to the outer wall 4.

The pail or bucket has a rolled lower edge at 3, and a rolled top at 10, providing stiffness and may include corrugations 11 and 12 to further stiffen the walls. When the aforesaid liquid has been placed in the 75 bucket there is laid on the top of the bucket a cover 13 which is adapted to rest on the rolled top 10 and which has a central opening 14 through which is inserted an inner 80 container 15 which usually contains a solution of sulphate of aluminum which is adapted to react with the bicarbonate of soda to produce carbon dioxide. The container 15 is lowered through the opening 14 until it is arrested by a suitable stop (not 85 shown), and then there is put upon it a cover 16 through the upper face of which projects the tail 17 of a weight 18 which may be of cast iron, and in that case is provided with a hard point 19 at its lower end 90 for a purpose which will presently appear.

The weight 18 is normally held in its upper position shown in Figure 1 by means of the heel 20 of a trigger 21 which overlies a pin 22 set across an opening 23 in the tail 95 17. This trigger is pivoted intermediate its ends at 24 upon standards 25, which are suitably fastened to the cover 16, the trigger being held in effective position to support the weight 18 through a chain 26 which extends downward near the outside of the wall 4 from the outer end of the trigger to near the bottom 3 of the bucket where it passes through an opening 27 in the wall 100.

beneath the bottom plate 2 and is anchored in a fusible link 5. The link 5, in turn, is anchored through a chain 28 to a thumb nut 29 at the side of the bucket in the side directly opposite the opening 27. Thus it comes about that the fusible link retains the weight 18 in its upper position.

In case of fire beneath the pail or bucket, the fusible link melts rapidly, releases the chain 26 and allows the weight 18 to fall through the container 15 until its sharp point 19 strikes and breaks a break-glass 30 which is suitably mounted in the bottom of container 15. The glass for this purpose lies between a flanged retainer 31 which is screw-threaded and fits onto a screw-threaded flange seat 32 and is screwed up against the seat so that the glass 30 is held between the rubber washers 33 and 34 which lie against the flanges on opposite sides of the glass and allow the retainer to be screwed up tight against the glass and bear on the seat. When the glass is broken, the solution of sulphate of aluminum flows into the solution of bicarbonate of soda, usually producing a froth because of the presence of froth-facients. In any event the bubbles of carbon dioxide released cause the liquid to expand and flow out through side openings 35 near the top of the bucket and in the outer wall 4 thereof.

According to the present invention means are provided for minimizing the large evaporation of water which normally takes place through the openings 35 because of the large surface of liquid exposed. This end is shown as attained by providing an internal wall or apron 36 which is fast to the cover 13 and is spaced away from the wall 4 a suitable distance. It is found that $\frac{3}{8}$ of an inch space between the apron or shield 36 and the wall 1 is sufficient space to allow the bucket extinguisher to work efficiently and yet is small enough to greatly minimize the evaporation of water. Not only does the apron 36 prevent evaporation of water from the surface with its circumference, but it also diminishes the evaporation by acting as a barrier against the circulation of air across and through the bucket. Thus the currents of air which would hasten evaporation are blocked. The apron or evaporation shield 36 may be of any convenient depth. A depth of about 55 4" has been found satisfactory for a two and one-half gallon pail. In such a pail the openings 35 are often upwards of two inches long and one inch high.

A plurality of deflectors 40 are secured to the wall 4 above the openings 35. These deflectors function primarily to deflect the froth downward as it passes through the openings 35, but they also cooperate with the apron 36 to further eliminate circulation 65 of air across and through the bucket which

would hasten evaporation of the liquid. The deflectors are preferably constructed of sheet metal and are adapted to be so bent or adjusted with respect to the wall 4 as to confine the foam to a given area beneath the extinguisher.

In order to prevent the chain 26 from being caught on anything external which may lie against the outer surface of the bucket 4, there is provided a long narrow metal cover or shield 38 which is secured to the outside of the bucket wall and extends from almost the level of the cover 13 down in the opening 27 through which the chain 26 passes. In order to facilitate the passing of the chain around the turn 27 it is found that nothing more is needed than a lug 39 providing a smooth surface to make the chain run easily over the space which would otherwise be occupied by the rugged edges of the bucket parts.

Having thus described certain embodiments of the present invention, what is claimed is:

1. In a fire extinguishing device of the foam type, an outer receptacle adapted to hold a liquid and having a plurality of unobstructed openings in its wall near the top thereof, a cover for said receptacle, an inner receptacle having its wall spaced from the wall of the first named receptacle and adapted to carry a liquid which when mixed with the first named liquid will produce a foam, means for causing the two liquids to commingle whereby a gas is generated and a foam is produced, and a depending wall within said outer receptacle near the wall thereof and extending below said openings to a point slightly below the normal liquid level of the first liquid, whereby the surface of the liquid in the outer receptacle from which evaporation takes place through said openings is reduced to a small part of the total area of the surface of the liquid in said outer receptacle, and whereby upon generation of gas only the upper portion of the liquid within the outer receptacle is ejected through said openings and the remaining liquid within the outer receptacle is prevented from escaping except as a foam.

2. In a fire extinguishing device of the foam type, an outer receptacle adapted to hold a liquid and having a plurality of unobstructed openings in its wall near the top thereof, a cover for said receptacle, an inner receptacle having its wall spaced from the wall of the first named receptacle and adapted to carry a liquid which when mixed with the first named liquid will produce a foam, means for causing the two liquids to commingle whereby a gas is generated and a foam is produced, and a depending wall within said outer receptacle near the wall thereof and extending below said openings to a point slightly below the

normal liquid level of the first liquid, whereby the surface of the liquid in the outer receptacle from which evaporation takes place through said openings is reduced to a small part of the total area of the surface of the liquid in said outer receptacle and whereby upon the generation of gas only the upper portion of the liquid within the outer receptacle is ejected through said openings and the remaining liquid within the outer receptacle is prevented from escaping except as a foam, and a plurality of bendable deflectors secured to the wall of the outer receptacle at points on the outer surface thereof above said openings for deflecting the foam in a downward direction as it is ejected from the outer receptacle through said openings. ¹⁵

In testimony whereof we have affixed our signatures to this specification.

GEORGE ENNIS FERGUSON.

LEWIS GOUVERNEUR MORRIS TIMPSON.
